UNITED STATES PATENT OFFICE

99,286

DESIGN FOR A HEADLIGHT

Jeremiah D. Kennelly, Oak Park, Ill.

Application February 3, 1936, Serial No. 60,958

Term of patent 7 years

To all whom it may concern:

Be it known that I, Jeremiah D. Kennelly, a citizen of the United States, residing at Oak Park, in the county of Cook and State of Illinois, have invented a new, original, and ornamental Design for a Headlight, of which the following is a specification, reference being had to the accompanying drawing, forming a part thereof, in which:

Figure 1 is a side view in elevation of the headlight, showing my new design; Fig. 2, a front view in elevation; and Fig. 3, a plan view.

I claim:

The ornamental design for a headlight as shown.

JEREMIAH D. KENNELLY.
